Fig. 3.

UNITED STATES PATENT OFFICE.

JOHN OLIPHANT, OF CHICAGO, ILLINOIS, ASSIGNOR TO SULLIVAN MACHINERY COMPANY, A CORPORATION OF MASSACHUSETTS.

BOOSTER.

1,401,946.

Specification of Letters Patent. Patented Dec. 27, 1921.

Application filed August 11, 1919. Serial No. 316,667.

To all whom it may concern:

Be it known that I, JOHN OLIPHANT, a citizen of the United States, residing at Chicago, in the county of Cook and State of Illinois, have invented certain new and useful Improvements in Boosters, of which the following is a full, clear, and exact specification.

My invention relates to boosters.

10 It has for its object to provide an improved booster especially adapted to use in connection with pumping liquid by fluid pressure, as for instance in air lift pumping or the like. A further object of my invention is to provide a booster of improved construction having improved and simplified mechanism adapted to improve the operation of separating the gas and liquid and propelling the latter from the booster, to enable 15 the condition of the latter at any time to be readily determined from a point outside the booster casing, and to provide a simplified and more inexpensive booster structure which may be more readily manufactured. 20 These and other objects and advantages of my improved construction will, however, hereinafter more fully appear.

For purposes of illustration, I have shown in the accompanying drawings one embodiment which my invention may assume in practice.

In these drawings,—

Figure 1 is a vertical sectional view of a booster constructed in accordance with my 35 invention, parts being broken away to show details of construction.

Fig. 2 is a transverse sectional view thereof on line 2—2 of Fig. 1.

Fig. 3 is a vertical sectional view of the 40 valve and float mechanism on a line corresponding to the line 3—3 of Fig. 2.

Fig. 4 is a detail view showing my improved construction equipped with a bottom discharge pipe.

45 In my improved construction it will be observed that I have shown a booster casing 1 in the form of a casting having an integral bottom 2 and an integral top 3. As shown, an aperture 4 is provided in and at 50 one side of the bottom adapted to receive a suitable riser 5, herein imperforate and discharging only at its upper end, and this riser is connected at its lower end to the upper end of an up-pipe 6 delivering the 55 mixture to the booster; flanges 7, 8 on the

members 5 and 6 being clamped together and to the casing by means of screws 9. In the top 3 of the casing, I have also provided an aperture 10, herein coaxially disposed over the open end of the riser 5 and adapted to receive a plate 11 attached to the top of the casing by screws 12 and having an umbrella surface 13 formed on its under side and located a substantial distance above the end of the riser 5. Here it will also be observed that apart from the riser 5, and herein on the opposite side of the casing therefrom, I have also provided a downwardly extending web 14, attached to, and herein formed integral with, the top of the casing and coöperating 65 with the side wall thereof to form a substantially cylindrical, closed, liquid discharge pipe or passage extending from the top of the casing to a point above the bottom thereof. Here it will also be noted that 70 above the discharge passage thus formed, and herein coaxially disposed therewith, I have likewise provided an aperture 15 adapted to be closed at will by a plate 16 attached to the top of the casing by screws 75 17, and that in the side wall of the casing 1, and adjacent the top of the discharge passage mentioned, I have provided another opening 18 adapted to be closed by the same plate and herein having a discharge pipe 19 80 clamped thereover by means of screws 20, the construction being such that the discharge pipe may be connected at will over either aperture 15, 18 and the remaining aperture 85 may then be closed by the plate 16. 90

Attention is here also directed to the fact that I have also provided an aperture 21 in the bottom 2 of the casing, preferably coaxially disposed with respect to the discharge passage formed by the web 14, which 95 not only facilitates coring during the casting operation, but, as shown in Fig. 4, is adapted to receive when desired an upstanding discharge receiving member or pipe 22 which extends upward into the discharge 100 passage mentioned and may or may not, at will, be provided with suitable openings 23, adapted to permit the discharge of liquid therethrough to the discharge line. Thus it will be observed that I have provided by the 105 construction shown, an alternative construction adapted to use when a discharge from the bottom of the booster casing is for any reason desired, the apertures 15 and 18 then preferably being closed by plates correspond- 110

ing to the plate 16, while at other times the aperture 21 is usually closed by a similar plate.

In my improved construction, it will also be observed that the top 3 of the casing is apertured, as at 24, at a point herein at one side of a plane passing through the axes of the riser 5 and the discharge passage formed by the web 14. Insertible within this aperture and carried on a plate 25 normally closing the same and attached to the top of the casing by screws 26, is a float frame 27, herein comprising a pair of rods fixed to the plate 25 at their upper ends and rigidly connected at their bottoms by a plate 28 having an axial aperture 29 therein adapted to receive and guide the lower end of a float rod 30 adjustably carrying a diving bell float 31 thereon at a point below the plate 25 and having a spring pressed relief valve mechanism 32 of the type described and claimed in my co-pending application Serial No. 135,386, filed December 6, 1916, on its upper end, controlling the connection between the interior of the casing and the discharge pipe 33. Herein it will also be observed that the frame 27 is partially inclosed by a guard, herein in the form of a tubular member 38 which is spaced apart at its opposite ends from the plate 28 and top 3 of the casing, the construction being such that the effect of surging upon the float, and therefore upon the valve, is minimized, at the same time that a baffle in the bottom of the casing is rendered unnecessary and the whole mechanism is made capable of being removed as a unit from the top of the booster casing.

In my improved construction it will also be observed that I have provided in the side wall of the booster casing 1, and herein opposite the riser 5, a plurality of apertures 39 and 40, of which the aperture 39 is disposed slightly below the top of the riser, while the aperture 40 is disposed slightly above the bottom of the discharge passage formed by the web 14. As shown, the flow through these apertures is controlled by manually adjustable escape valves, herein in the form of pet cocks 41 and 42, so that an operator by manipulating these pet cocks may readily determine the position of the liquid level in the booster during the operation thereof, although it will be understood that any usual gage may be connected between these openings if desired.

In the operation of a booster of the construction described, the mixture of gas and liquid enters the same through the riser 5, and through the action of the umbrella 13 is deflected downward toward the bottom of the casing; the liquid collecting at the bottom and the gas collecting at the top of the latter. Due to the action of the float controlled valve mechanism 32, the pressure in the

booster casing will be maintained at a predetermined amount sufficient to act upon the surface of the liquid at the bottom of the casing and cause a substantially constant flow of the same to be forced out through the discharge outlet formed by the web 14 and into the discharge pipe 19, whether the latter is disposed laterally over the aperture 18 or in its alternative position on the top of the casing and over the aperture 15. Similarly, it will be observed that the liquid will be caused to enter the pipe 22 when a bottom discharge is used, as illustrated in Fig. 4. It will further be observed that during this operation and while the pressure is maintained in the usual and desired manner by the float controlled valve 32, any objectionable effects of surging upon the valve are overcome by the tubular member 38, the valve thereby being enabled to move with freedom as necessary in accordance with the variations in liquid level indicated by the position of the float. Here it will also be observed that throughout the operation of the booster the operator is enabled whenever desired to determine the position of the liquid level therein by a simple manipulation of the pet cocks 41 and 42, these cocks being so disposed that when air flows through the pet cock 41 and liquid flows through the pet cock 42 the operator knows without further examination that the desired liquid level is being maintained; while on the contrary, if liquid flows out at the top, the operator knows that the air pressure in the booster is not being maintained, and if air blows from the lower pet cock that the air is not escaping through the mechanism 32 rapidly enough, and is thus in either case able to diagnose the difficulty and, through suitable adjustment of the valve mechanism 32, correct the same.

As a result of my improved construction, it will be observed that with the umbrella disposed on the top of the casing and well above the outlet of the riser 5, it is possible to eliminate the wall of liquid otherwise extending between the outlet of the riser and the top of the casing, and thereby permit the air to rise more freely to the top of the booster and reduce the amount of the same passing to the discharge, at the same time that the construction of the umbrella is simplified and cheapened. Through the use of my improved discharge passage including the web 14 and the plurality of liquid outlet openings communicating with the discharge passage formed thereby, it will also be observed that the construction is simplified and cheapened at the same time that it is made possible to adapt the booster to varying conditions, i.e. wherever a top, side, or bottom discharge is desired, and with any discharge maintain an effective flow through the discharge pipe, the discharge opening formed

by the web being closed at the top and extending well down into the liquid. In my improved construction it will also be observed that it is made possible to cheapen the entire construction by casting the booster casing and that the number of parts therein is reduced and all parts therein are readily removable, the umbrella as well as the valve and float being removable as units through the top of the casing. These and other advantages of my improved construction will, however, be clearly apparent to those skilled in the art.

While I have in this application specifically described one embodiment which my invention may assume in practice, it will be understood that this form is used for illustrative purposes and that the invention may be modified and embodied in various other forms without departing from its spirit or the scope of the appended claims.

What I claim as new and desire to secure by Letters Patent is:

1. A booster comprising a casing having a top and bottom and a discharge opening, and a web coöperating with the side wall thereof to form a discharge passage communicating with said opening and extending from the top of said casing to a point above the bottom thereof.

2. A booster comprising a casing having a top and bottom and a discharge opening in its top, and a web coöperating with the side wall thereof to form a discharge passage disposed substantially coaxially with said opening and extending from the top of said casing to a point above the bottom thereof.

3. A booster comprising a casing having a top and bottom and a discharge opening in its side, and a web coöperating with the side wall thereof to form a discharge passage communicating with said opening and extending from the top of said casing to a point above the bottom thereof.

4. A booster comprising a casing having a top and bottom and discharge openings in its top and side, and a web coöperating with the side wall thereof to form a discharge passage communicating with said openings and extending from the top of said casing to a point above the bottom thereof.

5. A booster comprising a casing having a plurality of discharge openings at its opposite ends including an opening in its bottom, a web coöperating with the side wall thereof to form a discharge passage extending from the top of said casing to a point above the bottom thereof, and means for closing the opening not in use.

6. A booster comprising a casing having a top and bottom and a plurality of discharge openings, a web coöperating with the side wall thereof to form a discharge passage communicating with said openings and extending from the top of said casing to a

point above the bottom thereof, a discharge pipe communicating with one of said openings, and means for closing the other opening.

7. A booster comprising a casing having a top and bottom and discharge openings in the top, bottom, and side thereof, a web coöperating with the side wall thereof to form a discharge passage communicating with said openings and extending from the top of said casing to a point above the bottom thereof, a discharge pipe communicating with one of said openings, and means for closing the other opening.

8. A booster comprising a casing, a mixture delivering riser therein, gas and liquid separating and discharging means therein including a discharge pipe having an open end disposed above the bottom of the casing, and a plurality of escape means disposed in the wall of said casing, one below the upper end of said riser and the other above the lower end of said discharge pipe.

9. A booster comprising a casing having inlet and discharge pipes therein, a float controlled valve mechanism carried by the top of said casing and including a float disposed in said casing and removable as a unit through the top thereof, and means for protecting said float including a guard surrounding said float and removable therewith through the top of said casing.

10. A booster comprising a casing having inlet and discharge pipes therein, a float controlled valve mechanism carried by the top of said casing and including a float disposed in said casing and removable as a unit through the top thereof, and a tubular member inclosing said float and spaced apart from the top of said casing removable there-through with said float.

11. A booster comprising a casing having inlet and discharge pipes therein, a float controlled valve mechanism carried on the top of said casing and including a float disposed in said casing and removable as a unit through the top thereof, and a tubular member inclosing said float and communicating with the interior of said casing at the top and bottom ends thereof, said tubular member being removable with said float.

12. A booster comprising a casing having inlet and discharge pipes therein, a float controlled valve mechanism carried by the top of said casing and including a float disposed in said casing and removable as a unit through the top thereof, a tubular member inclosing said float and spaced at its upper end from the top of said casing, and a plate arranged in alinement with the lower end of said casing and providing an annular opening between said tubular member and said plate.

13. A booster comprising a casing having a mixture inlet and separate liquid and gas

- 4 outlets therein and a web forming a discharge passage communicating with one of said outlets and extending from the top of the casing to a point above the bottom thereof, a float controlled valve mechanism carried by and removable as a unit through the top of said casing and having a float disposed in said casing outside said web, and a plate carried on the top of said casing and disposed above said inlet having an umbrella surface formed on the surface thereof adjacent said inlet.
- 10 14. A booster comprising a casing having a mixture inlet and separate liquid and gas outlets therein and a web coöperating with the casing wall to form a discharge passage communicating with said liquid outlet and extending from the top of the casing to a point above the bottom thereof, a float controlled valve mechanism carried by and removable as a unit through the top of said casing and having a float disposed in said casing outside said web, a plate carried on the top of said casing and disposed above said inlet having an umbrella surface formed on the surface thereof adjacent said inlet, and a plurality of manually controlled escape valves, one disposed below the discharge of said inlet and the other disposed above the intake of said discharge passage.
- 15 15. A booster comprising a casing having a mixture inlet and separate liquid and gas outlets therein and a web coöperating with the casing wall to form a discharge passage communicating with said liquid outlet and extending from the top of the casing to a point above the bottom thereof, a float controlled valve mechanism carried by and removable as a unit through the top of said casing and having a float disposed in said casing outside said web, a tubular guard inclosing said float and removable therewith through the top of the casing, a plate carried on the top of said casing and disposed above said inlet having an umbrella surface formed on the surface thereof adjacent said inlet, and a plurality of manually controlled escape valves, one disposed below the discharge of said inlet and the other disposed above the intake of said discharge passage.
- 20 25

In testimony whereof I affix my signature.

JOHN OLIPHANT.
